COMBINATION HOIST AND AERIAL TRAM

Herbert L. Hite, Yuba City, Calif.

Application January 17, 1934, Serial No. 707,028

3 Claims. (Cl. 214—60)

This invention relates to what may be termed a combination hoist and aerial tram the same being especially designed to facilitate the handling of waste material or pay dirt of mines and at the same time to do away with bins and cars operated by hand over tracks.

The invention together with its objects and advantages will be best understood from a study of the following description taken in connection with the accompanying drawings wherein:

Figure 1 is an elevational view showing the application of the invention with the car in position for dumping the contents thereof.

Figure 2 is an enlarged view partly in section and partly in elevation showing the location of the parts with the car as it approaches the mouth of the mine shaft.

Figure 3 is an enlarged perspective view somewhat similar to Figure 2 with certain parts of the apparatus omitted.

Figure 4 is a top plan view of a carriage.

Figure 5 is a perspective view of a trip mechanism.

Figure 6 is a perspective view of a trip plate.

Figure 7 is a perspective view of a keeper plate to be hereinafter more fully referred to, and

Figure 8 is a perspective view of a spring latch.

Referring to the drawings by reference numerals it will be seen that 10 designates generally a mine shaft that is inclined at an angle to the perpendicular. Leading from the mouth 11 of the mine shaft is a track 12 which is a continuation of the inclined track 12' provided in the mine for the car 13. The car 13 is of any suitable construction and includes among other parts suitable wheels 14, and a vertically swinging hinge bottom 15 provided at the forward end of the car transverse keeper bar 16 with which are engageable pivoted latches 17. At its forward end the car 13 is also provided with a suitable bail 18 to which is secured one end of a draft cable 19 provided for drawing the car 13 along the inclined track out of the mine. Other suitable mechanism will of course be provided for the cable 19.

An inclined tram cable 20 is anchored at its lower end at the mouth of the mineshaft as clearly shown in the drawings and suspended from the cable 20 is what may be termed a skeleton clevis, or carriage, or cradle designated by the reference numeral 21.

The cradle 21 comprises a pair of inverted cross bars 22 to the ends of which are secured opposed angle iron tracks 23. Between the ends

thereof the bars 22 are connected by slightly spaced parallel angle bars 24 and rising from the bars 24 adjacent the ends thereof are brackets 25 in which are journaled sheaves 26 that ride along the cable 20 at the underside of the cable. Inwardly from the brackets 25 are brackets 27 that are braced with respect to the bars 22 by diagonal braces 28. Journaled in the brackets 27 are sheaves 29 that ride on the cable 20 at the top of the cable. The cradle, carriage or clevis 21 has the tracks thereof at the lower end curve downwardly so that rollers 30 provided on opposite sides of the car 13 may easily ride thereonto when the clevis is in the position shown in Figure 2 and as the car 13 passes from the shaft 15 through the mouth 11 thereof. The movement of the car 13 inwardly of the cradle or clevis 21 is arrested through the medium of stops 31 provided on the tracks 23 as shown in Figure 3.

For releasably retaining the car and cradle 20 or clevis interengaged there is provided at the rear or lower end of the cradle a transversely mounted shaft 32 that is normally urged to rotate in a clockwise direction through the medium of a coil spring 33. On one end of the shaft 32 there is provided a latch member 34 that is adapted to engage behind the rear end of the car 13 as shown in Figure 3, and with the forward rollers 30 engaged with the stops 31 and the latch member 34 engaged with the rear end of the car 13 it will be apparent that the car will be held in position within the cradle and a further pull on the draft cable 19 will cause the cradle with the car suspended thereby to move from the position shown in Figure 2 to the position shown in Figure 1 thus bringing the car 13 to the terminus of the track 12. At this point the car 13 is relieved of its load. For releasing the bottom of the car for dumping purposes a suitable trip mechanism is provided. This trip mechanism includes a skeleton frame structure 35 in which are suitably journaled upper and lower sheaves 36, 37 the upper sheave 36 riding on the cable 20 and the lower sheave 37 having trained thereover the draft cable 19 as shown in Figure 1. There is also journaled in the skeleton frame structure of the trip device a sheave 38 disposed in advance of the sheave 36 and engaging the under side of the cable 20. For adjusting the trip device 35, and for securing the same at the desired position there are provided suitable cables 39, 40 with which suitable winches or other mechanism (not shown) will be provided for exerting the necessary tension thereon. Carried

by the skeleton member 35 is a transverse trip bar 41 the ends of which are arranged in the path of the latches 17, and when these latches are brought into engagement with the ends of the bar 41 the latches are tripped, that is to say rocked in an anti-clockwise direction out of engagement with the keeper bar 16 thus permitting the bottom 15 of the car 13 to swing downwardly as shown in Figure 1 for dumping the contents of the car. For limiting the downward swinging movement of the bottom 15 there are provided suitable chains 42.

Means is provided for releasably locking the cradle, carrier or clevis 21 in position at the mouth 11 of the mine shaft as shown in Figure 2, and such means consists in the present instance of a keeper plate 43 that is provided with attaching flanges 44 whereby it is secured by suitable fastening elements to the frame of the mouth 11 as suggested in Figure 2. Cooperable with the keeper plate 43 is a latch member 45 that is provided with an offset portion intermediate its end, and at said offset portion is pivoted between bars 24 as at 46. At its pivoted end the latch is connected by a link 47 with a lever 48 that is pivoted between the bars 24 as at 49. The lever 48 is normally urged to rotate in an anti-clockwise direction through the medium of the spring 50 for releasably retaining the latch member 45 engaged with the keeper plate 43. To release the car 13 when the car together with the carrier 21 approaches the mouth 11 of the mine shaft there is suitably secured to the frame work about the mouth 11 of the mine shaft a trip plate 51 with which is engageable an arm 52 provided on the free end of the shaft 32. Obviously as the cradle 21 approaches the mouth of the mine shaft arm 52 will be moved into engagement with the plate 51 in a manner to cause shaft 32 to rotate in an anti-clockwise direction to raise the latch 34 and thus release the car 13. With the car 13 thus released cable 19 may be paid out to permit the car 13 to back down into the mine shaft.

On opposite sides of the track 12 adjacent to the mouth 11 of the mine shaft there are provided suitable, elevated guard rails 53 for guiding the carriage, cradle or clevis 21 while shorter and lower guard rails 54 are provided to guide the car 13.

At the forward or raised end of the cradle, clevis or carriage 21 there is also provided a sheave 55 over which is trained the draft rope 19. It will also be apparent that on a return of the car 13 from the position shown in Figures 1 or 3 to, for example, the position shown in Figure 2 the bottom 15 of the car is caused to swing upwardly to a closed position by coming into contact with the ends 12a of the rails of the track 12, which ends 12a are turned downwardly as will be noted for that purpose.

Also, for releasing the latch 25 there is provided at the top of the car 13 and extending

across the front end of the car a bar 55 in the path of which is arranged the free end of the lever 48. Thus it will be seen that as the car 13 moves inwardly onto the cradle 21 bar 55 will come into contact with said free end of the lever 48 causing the latter to swing about its pivot 49 in a clockwise direction resulting in a similar swinging movement being imparted to the latch 45 for lifting the latch out of engagement with the keeper plate 43 thus freeing the cradle 21 so that the latter together with the car now suspended therefrom may be moved upwardly to the dumping position shown in Figure 1.

Having thus described my invention, what I claim as new is:

1. In a device of the character described, an inclined tram cable, a cradle suspended from said cable and movable therealong, opposed spaced tracks carried by said cradle, a car, rollers on opposite sides of the car and engageable with the tracks of the cradle for suspending the car from the cradle, and a latch member pivotally mounted on one end of the cradle and engageable with a corresponding end of the car, stop members on said tracks at the end thereof remote from said latch member and cooperable with the latch member for holding the car against longitudinal movement relative to the cradle.

2. In a device of the character described, a cradle, suspension means for the cradle and along which the cradle is constrained to move, track members on the cradle, a car, rollers on the car engageable with the tracks of the cradle for suspending the car from the cradle, inter-engaging means on the cradle and the car for retaining the car engaged with the cradle, said car including a hinged bottom provided with a keeper bar, and pivoted latch members on the car engageable with the keeper bar, and a trip device arranged in the path of the cradle and including a traveling frame structure and a transverse trip bar carried thereby and arranged to engage the latch members on the bar for tripping the latches to free the bottom of the car.

3. The herein described material handling mechanism consisting of a traveling cradle and a trip device having substantially the same path of movement, a car, inter-engaging means on the car and the cradle for guiding the car onto the cradle and for suspending the car from the cradle, means on the cradle engageable with opposite ends of the car for securing the same against longitudinal movements relative to the cradle, said car being provided with a pivoted bottom, latch means for securing the bottom in a normal position, and means on the trip device engageable with the latch means for operating the latter to release the bottom of the car as the cradle and car approach the trip device, and means for securing the trip device at a set position relative to the cradle.

HERBERT L. HITE.
